UNITED STATES PATENT OFFICE

147,481

DESIGN FOR A RADIO PHONOGRAPH CABINET

Melson J. Wachsman, Grand Rapids, Mich., assignor to Wilcox-Gay Corporation, Charlotte, Mich., a corporation of Michigan

Application March 21, 1946, Serial No. 127,751

Term of patent 14 years

(Cl. D56—4)

To all whom it may concern:

Be it known that I, Melson J. Wachsman, a citizen of the United States, residing at Grand Rapids, in the county of Kent and State of Michigan, have invented a new, original, and ornamental Design for a Radio Phonograph Cabinet, of which the following is a specification, reference being had to the accompanying drawing, forming a part thereof.

Figure 1 is a view in perspective of my novel ornamental radio phonograph cabinet. The left side of the cabinet is identical with the visible right side.

Figure 2 is a cross-sectional view taken on line 2—2 of Figure 1.

Figure 3 is a cross-sectional view taken on line 3—3 of Figure 1.

I claim:

The ornamental design for a radio phonograph cabinet, as shown and described.

MELSON J. WACHSMAN.
